CONTROL FOR BARREL STENCILLING MACHINES

Filed Sept. 24, 1946

UNITED STATES PATENT OFFICE

2,439,949

CONTROL FOR BARREL STENCILLING MACHINES

John E. Roblee, Pittsburgh, Pa., assignor to Westinghouse Electric Corporation, East Pittsburgh, Pa., a corporation of Pennsylvania

Application September 24, 1946, Serial No. 698,971

5 Claims. (Cl. 318—35)

1

This invention relates generally to automatic control systems and more particularly to a system for effecting alternate operation of a pair of members to be controlled in dependence of the position of the respective members.

More particularly, this invention is directed to an apparatus for automatically stencilling barrels in which a member is utilized to pick up said barrels, position said barrels for stencilling operation thereon by a stencilling member and thereafter discharging said barrels, the stencilling member comprising a stencilling screen movable first in one direction across a properly positioned barrel and upon the positioning of a second barrel for stencilling being movable in the opposite direction across said second barrel, electrical interlocking between said stencilling member and said barrel pickup member being utilized to automatically control the alternate cyclic operation of said members.

Generally, it is an object of this invention to provide an automatic barrel stencilling machine.

Another object of this invention is to provide a control arrangement for controlling the operation of a pair of members to be alternately operated in which each of said members, at the limits of movement of each thereof, are operable to initiate operation of the other of said members.

A further object of this invention is to provide a system of electrical control which is simple in its elements and positive in operation.

The foregoing objects are merely illustrative of the various aims and objects of this invention. Other objects and advantages will become apparent upon a study of the following specification when considered in conjunction with the accompanying drawing, in which, the single figure thereof illustrates a system of electrical control embodying the principles of this invention.

In the drawing, the elements of the barrel stencilling machine which are to be controlled are diagrammatically illustrated. These elements include a yoke 1 constructed and arranged to pick up barrels 2, the yoke being driven by a motor 2M, and a rectangular framework 3 shown only in side elevation partly in section and driven by the motor 1M, which carries a stencilling screen 4 disposed to contact and stencil the barrels 2. The framework 3 is supported in suitable guides or tracks (not shown) which permit movement of the framework in the forward and reverse directions, respectively, left and right as viewed in the drawing. The framework is in its inter-

2

mediate position indicating that a stencilling operation is in progress.

The electrical elements comprising the system for controlling the motors 1M and 2M and thus controlling the movements of the yoke 1 and the framework 3 include the limit switches L1 and L2 operated by the dogs 5 and 6 on the framework 3, the limit switches L3 and L4 operated by the cams 7 and 8 on the shaft of motor 2M, the forward and reverse relays F and R alternately energized in dependence of the position of the framework 3 at one or the other of its extremes of movement through interlocking circuits of the limit switches and which control the direction of rotation of the motor 1M, the relay B which energizes the armature of the motor 2M whenever the framework 3 is in one of its two extremes of position, this control of the motor 2M also being effected through the limit switches. The control further includes the Inch Forward, Inch Reverse and Inch Barrel push buttons which provide presetting and inching control of the respective positions of the yoke 1 and framework 3, and finally the conventional starting control including the switch NV, the Start and Stop push buttons, and the selector switch SS having the two positions Run and Inch, respectively, for automatic and manual system control. A source of alternating current for energizing the system is represented by the conductors 10, 11 and 12.

The yoke 1 is provided with four arms displaced by 90° each two forming a cradle in which the barrel rides beneath the screen. Rollers 9 positioned near the extremities of the yoke arms support the barrel in the yoke that barrel rotation may occur by frictional engagement thereof with the moving screen during a stencilling operation. The extremities of the yoke arms are curved in the direction of yoke rotation to provide suitable means for picking up the next barrel to be stencilled. With the arrangement shown, the barrels may be fed to the yoke by means of a ramp (not shown) sloping into the yoke. For each stencilling operation, the yoke 1 is rotated 90° in the clockwise direction. During a normal cycle, one barrel is engaged by the curved extremities of the yoke arm, another is being stencilled and a third (not shown) is discharged.

The three phase alternating current motors 1M and 2M are connected in circuit branches extending from the three phase alternating current supply represented by conductors 10, 11 and 12. Energization of the motors through these branches is controlled by relays. In the case of motor 1M which is to be intermittently operated

in reversed directions, reversible energization control is had through the medium of relay F or R, the direction of rotation of the motor, that is, forward or reverse, depending respectively upon which of relays F or R operate. Since the yoke 1 is to be intermittently operated in one rotational direction only, reversing means need not be provided. A single relay B is, therefore, utilized to intermittently connect the motor to supply conductors 10, 11 and 12. For automatic operation the coils of relays F, R and B are connected in separate circuits with certain of the limit switches across the conductors 10a and 12a. For manual operation the coils of these relays are connected across conductors 10a and 12b. Conductor 10a is energized through contacts NV1 of the no voltage switch NV. Conductors 12a and 12b are alternately energized through contacts NV2 in dependence of the position of selector switch SS. The coil of no voltage switch NV is connected across conductors 10 and 12 in a circuit including the Stop and Start push buttons.

Specifically, the coil of forward relay F is connected in a circuit across the conductors 10a and 12a which includes limit switch contacts L3b and L1a and across the conductors 10a and 12b in a circuit including the limit switch contacts L1a and the Inch Forward push button. The coil of reverse relay R is connected in a circuit across the conductors 10a and 12a which includes the limit switch contacts L2a and L4b and across conductors 10a and 12b in a circuit including limit switch contacts L2a and the Inch Reverse push button. The coil of relay B is energized from the conductors 10a and 12a during automatic control in a circuit including the paralleled pairs of limit switch contacts L1b, L4a and L2b, L3a. During inching operation the coil of this relay is connected between conductors 10a and 12b by the Inch Barrel push button.

This arrangement provides completely automatic control of the stencilling framework and yoke when the selector switch is set in its Run position. Under this condition relays F, R and B when sequentially connected across the conductors 10a and 12a by the limit switches in circuit therewith are energized, since conductors 12a are now connected to the supply. When the selector switch is in its Inch position the energy supply is transferred from conductors 12a to conductor 12b. Limit switches L3b, L4b and the paralleled pairs of limit switches L1b, L4a and L2b, L3a are disconnected from the circuit and their control effect respectively on relays F, R and B is no longer present. In the case of the stencilling framework the operation now depends upon the manipulation of the Inch Forward and Inch Reverse push buttons with limit switches L1a and L2a yet controlling the extreme of movement in each direction. Relay B is controlled exclusively by the Inch Barrel push button and may be utilized to actuate the yoke to any desired angular position.

As illustrated in the drawing, the various control elements are set so that automatic operation of the motor 1M in the forward direction will be had. This means that the selector switch SS is in its Run position, as shown. When the Start push button is pressed to energize the switch NV, the contacts NV1, NV2 and NV3 thereof close. Contacts NV1 and NV2 connect the conductors 10a and 12a to the source of energizing potential and contacts NV3 shunt the Start push button and provide a holding circuit for the coil of the NV switch.

The coil of forward relay F is now energized in a circuit across the conductors 10a and 12a including the limit switch contacts L1a and L3b which as shown are closed. Contacts F1, F2 and F3 are, therefore, closed and the motor 1M energized to drive the framework 3 in the forward direction stencilling the barrel 2 in contact with the screen thereof. When the extreme of forward movement is reached dog 5 actuates limit switch L1 opening contacts L1a and closing contacts L1b. Closing of contacts L1b completes an energizing circuit for the coil of relay B across conductors 10a and 12a which includes the contacts L4a and contacts L1b. Relay B picks up closing its contacts in the armature circuit for the motor 2M. As the motor 2M rotates, the yoke 1 is rotated discharging the stencilled barrel, positioning another barrel for stencilling and engaging a third barrel at the curved extremity of one arm thereof. Simultaneously therewith cams 7 and 8 are rotated. Limit switch L3 is actuated by cam 7 to open contacts L3b thereof shortly after cam rotation begins. Subsequently contacts L3a close. Limit switch L4 remains in the position shown until the yoke has rotated the required 90° to position the next barrel for stencilling. At this point, a sharp drop in the surface of cam 8 permits the biasing of the limit switch to its opposite position, opening contacts L4a and closing contacts L4b. Opening of contacts L4a stops the motor 2M by deenergizing the relay B. It is to be noted that the cams 7 and 8 are displaced by 90° and that the diametrically opposite halves of each thereof are symmetrical. Thus for each 90° of yoke rotation the limit switches L3 and L4 are reversely actuated.

When the contacts L4b close, the coil of relay R is connected across conductors 10a and 12a in a circuit which includes contacts L4b and contacts L2a. Contacts R1, R2 and R3 now close and the motor 1M is reversely connected to the conductors 10, 11 and 12. Consequently, the motor now runs in a reverse direction driving the framework 3 in the reverse direction. Screen 4 passes across the barrel to be stencilled and applies the stencil work thereto, the barrel being rotated by frictional engagement thereof with the screen. As the reverse direction extreme of movement is reached, the limit switch L2 is operated. Contact members L2a open while contact members L2b close. Opening of contacts L2a causes relay R to drop out and motor 1M is deenergized and stopped.

Closure of contacts L2b energizes relay B in a circuit including the contacts L3a and L2b. Motor 2M rotates until the yoke moves through the required 90° angle at which point the surface of cam 7 is cut back. Limit switch L3 again assumes the position shown in the drawing interrupting the circuit to relay B which drops out and deenergizes the motor 2M. Contacts L3b in conjunction with contacts L1a now pick up relay F and the cycle is repeated as described.

To effect inching movement of the yoke and framework, the selector switch is placed in the Inch position. Conductor 12b is now energized. Assuming the limit switch L1 in the position shown forward inching of the framework 3 is obtained by pressing of the Inch Forward push button, which, in conjunction with contacts L1a, energizes the F relay. This inching movement may continue until dog 5 opens contacts L1a. Reverse inching is accomplished by operation of the Inch Reverse push button which together with contacts L2a controls relay R. Inch movement

of the yoke 1 is obtained by operating the Inch Barrel push button. This push button directly controls the energization of relay B and motor 2M to effect inching operation of the yoke 1.

The foregoing disclosure and the showing made in the drawing are merely illustrative of the principles of this invention and are not to be interpreted in a limiting sense. The only limitations are to be determined from the scope of the appended claims.

I claim as my invention:

1. A control system for a pair of motors comprising, in combination, means for supplying electrical energy to said motors, a pair of relays for reversibly connecting one of said motors to said means for supplying electrical energy, a third relay for connecting the other of said motors to said means for supplying electrical energy, a reciprocating member driven by said one motor, and operable to each of two extremes of position, a rotatable member, constructed and arranged for intermittent rotation through a predetermined angle and driven by said other motor, first and second switches having normal positions and actuated positions, each of said switches being disposed for actuation by said reciprocating member, one at each extreme of movement thereof, third and fourth switches each having two positions of operation, one a normal position and one an actuated position, means for operating said third and fourth switches so that one is in its normal position when the other is in its actuated position for each intermittent movement of said rotatable member through said predetermined angle, circuit means connecting one of said pair of relays in circuit relation with said first and third limit switches to effect energization of said one relay when said first and third switches are in normal positions, circuit means connecting the other of said pair of relays in circuit relation with said second and fourth switches to effect energization of said other of said pair of relays when said second and fourth switches are in normal positions, circuit means connecting said third relay in circuit relation with said first and fourth switches to effect energization thereof when said first and fourth switches are in actuated positions, and circuit means connecting said second and third switches in circuit relation with said third relay to effect energization thereof when said second and third switches are in actuated positions.

2. A motor control system comprising, in combination, a first motor, a second motor, means for supplying electrical energy, a pair of relays for reversibly connecting said first motor to said means for supplying electrical energy, a third relay for connecting said second motor to said means for supplying electrical energy, means for limiting the rotational movements of said first motor in each of its two rotational directions including first and second switches, each having a normal position and an actuated position, means driven by said first motor for actuating said first and second switches, third and fourth switches, each having a normal position and an actuated position, means driven by said second motor for operating said third and fourth switches, constructed and arranged to position the third switch in its normal position and the fourth switch in its actuated position during one portion of the operating cycle of said second motor and to reverse the position of the third and fourth switches during another portion of the operating cycle of said second motor, means for energizing

one of said pair of relays when the first and third switches are in normal position, means for energizing the other of said pair of relays when the second and fourth switches are in normal position, means for energizing the third relay when the first and fourth switches are in actuated positions, and means for energizing the third relay when the second and third switches are in actuated positions.

10 3. In a control system for controlling the operation of an oscillatable member and a unidirectionally operable member, the combination of, a first motor for driving the oscillatable member, means for supplying electrical energy to effect reversible operation of said first motor, a second motor for driving said member to be unidirectionally operated, second control means for connecting said second motor to said means for supplying electrical energy, switch means responsive to the movements of said oscillatable member upon movement of said oscillatable member to each of its extremes of position, switch means responsive to movements of said unidirectionally operable member, and interlocking circuit means connecting said switch means responsive to movements of said oscillatable member, said switch means responsive to said unidirectionally operable member and said first and second control means for effecting alternate operation of said first and second control means.

4. In a control system for effecting alternate operation of a reversible member and a unidirectionally operated member, the combination of a first motor for driving said reversible member, a second motor for driving the unidirectionally operated member, means for energizing said second motor when said reversible member is in one extreme of position, means for deenergizing said second motor upon predetermined movement of said unidirectionally operated member, means operable when said unidirectionally operated member is stopped and said reversible member is in said one extreme of position for energizing said first motor to effect operation thereof to drive said reversible member to its other extreme of position, means operable when said reversible member reaches its other extreme of position for deenergizing the first motor, means operable upon movement of said reversible member to said other extreme of position for energizing said second motor, means for deenergizing said second motor upon predetermined movement of said unidirectionally operated member, means operable when said unidirectionally operated member is stopped for reversibly energizing said first member to effect operation of said reversible member in a reverse direction toward said one extreme of position, and means for deenergizing said first motor when said reversibly operated member reaches said one extreme of position.

5. In a control system for effecting alternate operation of a reversibly operated member and a unidirectionally operated member, the combination of, means for supplying electrical energy, a first motor for driving said reversibly operated member, a second motor for driving said unidirectionally operated member, a pair of relays for reversibly connecting said first motor to said means for supplying electrical energy, a third relay for connecting said second motor to said means for supplying electrical energy, means for energizing said third relay when said reversibly operated member is in one extreme of position to energize said second motor and drive said unidirectionally operated member, means for deen-

ergizing said third relay upon predetermined movement of said unidirectionally operated member, means for energizing one of said pair of relays when said unidirectionally operated member is stopped to effect energization of said motor to drive said reversibly operated member toward the other extreme of movement thereof, means for deenergizing said one of said pair of relays when said reversible member reaches said other extreme of movement thereof, means for energizing the third relay upon movement of said reversible member to said other extreme of movement thereof to effect energization of said second

motor and operation of said unidirectionally operated member, means for deenergizing said third relay upon predetermined movement of the unidirectionally operated member, means for energizing the other of said pair of relays upon stopping of said unidirectionally operated member to effect reverse energization of said first motor and operation of said reversibly operated member in the direction of said one extreme of position, and means for deenergizing said other of said pair of relays upon movement of said reversibly operated member to said one extreme of position.

JOHN E. ROBLEE.
